Filed Apr. 26, 1965, Ser. No. 84,958

Term of patent 14 years

(Cl. D26—13)

FIG. 2

FIG. 1

FIG. 6

FIG. 1 is a front elevation view of a motor starter housing showing our new design;

FIG. 2 is a rear elevation view;

FIG. 3 is a top plan view;

FIG. 4 is a side elevation view, the opposite side being substantially a mirror image thereof;

FIG. 5 is a bottom plan view; and

FIG. 6 is a left side, top and front perspective view.

The dominant features of the invention reside in those portions of the drawing shown by means of full lines.

We claim:

The ornamental design for a motor starter housing, as shown and described.
